ELECTRIC TOOTH BRUSH

William Thomas Brennan, Dunmore, Pa.

Application September 15, 1953, Serial No. 26,805

Term of patent 14 years

(Cl. D9—2)

To all whom it may concern:

Be it known that I, William Thomas Brennan, a citizen of the United States, residing at Dunmore, in the county of Lackawanna and State of Pennsylvania, have invented a new, original, and ornamental Design for an Electric Tooth Brush, of which the following is a specification, reference being had to the accompanying drawing, forming part thereof.

Figure 1 is a plan view of an electric tooth brush, showing my new design;

Figure 2 is a side elevational view thereof;

Figure 3 is an end view of the same; and

Figure 4 is a fragmentary view of a central

portion of the brush, showing the side opposite the side shown in Figure 1.

I claim:

The ornamental design for an electric tooth brush, as shown.
